UNITED STATES PATENT OFFICE

121,643

DESIGN FOR A MAT OR SIMILAR ARTICLE

Mary C. McGee, Hempstead, N. Y.

Application June 29, 1940, Serial No. 93,325

Term of patent 3½ years

To all whom it may concern:

Be it known that I, Mary C. McGee, a citizen of the United States of America, residing in Hempstead, county of Nassau and State of New York, have invented a new, original, and ornamental Design for a Mat or Similar Article, of which the following is a specification, reference being had to the accompanying drawing, forming part thereof, wherein the figure is a plan view of a mat showing my new design. I claim:

The ornamental design for a mat or similar article, as shown.

MARY C. McGEE,
